UNITED STATES PATENT OFFICE.

OSKAR F. THORN, OF CHICAGO, ILLINOIS, ASSIGNOR OF ONE-THIRD TO GUSTAF HULLGREN, OF CHICAGO, ILLINOIS.

PLANING-MACHINE.

1,075,739.

Specification of Letters Patent.

Patented Oct. 14, 1913.

Application filed June 26, 1912. Serial No. 705,992.

To all whom it may concern:

Be it known that I, OSKAR F. THORN, a citizen of the United States, and a resident of the city of Chicago, county of Cook, and 5 State of Illinois, have invented certain new and useful Improvements in Planing-Machines, of which the following is a specification.

My invention relates to planing machines 10 and particularly to machines for planing the frames of pianos, as hereinafter described.

The object of this improvement is to provide a device which will at one operation 15 plane the sides and edges of the piano back with curved surfaces and to provide a simple and effective machine for accomplishing this result.

Other objects will appear hereinafter. 20 The invention consists in the combinations and arrangements of parts hereinafter described and claimed.

The invention will be more readily understood by reference to the accompanying 25 drawings forming a part of this specification, and in which,

Figure 1 is a plan view of my invention, Fig. 2, a longitudinal vertical section of the same, Fig. 3, an end view of the same, and 30 Fig. 4, a fragmental section of the work locking clamp.

The preferred form of construction as illustrated in the drawings comprises a curved track 5 having the highest point of 35 such track immediately under the planing head. The track 5 is provided with ears 6 which are supported by means of adjusting screws 7 threaded in the ears 8 of the supports 9, and is supported in such adjustable 40 supports in a manner to be flexed in a greater or less curve as desired. Such curvature is altered by means of adjusting the track in the supports 9 by means of the screws 7, as will be readily understood by 45 reference to the drawings.

A car 10 is provided with supporting wheels 11 and axles 12 by which it is mounted on the track 5 and adapted to move longitudinally of such track. The car 10 50 is provided with guides 13 on its top portion and extended transversely thereof. A work supporting frame 14 is mounted to slide transversely on the car in the guides 13 to support the work during the planing operation. The frame 14 is provided with a bar

15 secured in the side portions of its frame, as indicated in the drawings, and said bar 15 is provided with rollers 16 which are adapted to engage the stops 17 upon transverse sliding of such supporting frame 14 60 to the side of the car, as indicated in Fig. 3. Such stop 17 also co-acts with the rollers 16 to form a pivotal joint for swinging the supporting member 14 to its unloading and loading position. Upon swinging the sup- 65 porting frame 14 to the position indicated in Fig. 3, the work is placed thereon and supported by the hooked end 14' of its lower portion and the adjustable clamps 18 are moved to their engaging position with 70 the work in order to secure the work on said supporting frame 14. Said adjustable clamps 18 are provided with slots 19 and secured to the frame 14 by means of bolts 20 as clearly illustrated. After securing the 75 work to the supporting frame 14, said supporting frame is swung on its pivotal point at 16 to its horizontal position and slid to its normal position on the car, as indicated by the dotted lines in Fig. 3. The locking 80 clamp 21 is then swung to its engaging position with the cross bars of the piano back, as indicated in Fig. 4. Such locking clamp is provided with a slot 22 formed of such a size that it may be removed from the head 85 23 of the locking bolt 24 when so desired. The locking member 21 is maintained in clamping position on the cross bars of the piano back by means of the bolt 24, which passes through the car 10 and secured to 90 the lever 25 by means of suitable nuts 26, or any other suitable connecting means. Said lever 25 is pivoted to the car frame as at 27 and provided with a locking catch 95 28 which is adapted to engage the locking means 29. Such locking means 29 is secured to the under side of the car 10, as indicated in the drawings so that upon downward and transverse movement of the lever 25, the work and supporting frame 14 will be firmly 100 clamped to the top of the car 10.

Cutters 30 are formed with curved cutting edges, as clearly illustrated in the drawings, and secured to the shaft 31 by means of screws 32 which are passed through slots 105 33 in such cutting blades. The shaft 31 is mounted in suitable housings 34 in a manner to be rotated by a suitable source of power connected therewith by means of the pulley 35 carried on said shaft. The car 10 110

is moved upon the track by means of the gears 36, 37, 38 and the rack 39, as clearly illustrated. The gears 37 and 38 are mounted on a stud 40 which is secured in the housing 34, as clearly indicated in Figs. 2 and 3 so that upon rotation of the shaft 31 the car, supporting the work, will be moved on the track under the cutting blades 30 to effect the planing of the piano back at one 10 passage of such cutting blades. The work in passing over the curved track under the cutting blades 20 will cause the surface of the work to be planed in a curve, as indicated particularly in Fig. 2, and the curvature of the cutters 30 will effect the planing of the back in a curve as indicated particularly in Fig. 3, thus forming all of the sides of such piano back in the curves, as clearly illustrated.

20 While I have illustrated and described the preferred form of construction for carrying my invention into effect, this is capable of variation and modification without departing from the spirit of the invention. I, 25 therefore do not wish to be limited to the precise details of construction set forth, but desire to avail myself of such variations and

modifications as come within the scope of the appended claims.

Having described my invention what I 30 claim as new and desire to secure by Letters Patent is:

1. The combination with a truck, of a support mounted to slide thereon; and a clamp on said truck adapted to secure work on said support and also secure said support to said truck, substantially as described.

2. The combination with a truck, of a work support mounted to slide transversely thereon; means limiting the sliding motion 40 in one direction of said work support on said truck and providing a pivotal point upon which said work support is swung from a horizontal to vertical positions and a clamp on said truck adapted to secure 45 work on said support and secure said support to said truck.

In testimony whereof I have signed my name to this specification in the presence of two subscribing witnesses.

OSKAR F. THORN.
